UNITED STATES PATENT OFFICE.

ADDIE DEMING, OF WINDSOR, ONTARIO, CANADA.

CURTAIN-FIXTURE.

1,231,336.

Specification of Letters Patent. Patented June 26, 1917.

Application filed January 8, 1917. Serial No. 141,147.

To all whom it may concern:

Be it known that I, ADDIE DEMING, a subject of the King of Great Britain, residing at Windsor, in the county of Essex and 5 Province of Ontario, Dominion of Canada, have invented certain new and useful Improvements in Curtain-Fixtures, of which the following is a specification, reference being had therein to the accompanying 10 drawings.

This invention relates to curtain fixtures, and the primary object of my invention is to furnish a window frame, doorway or alcove with novel pivoted curtain rods that 15 permit of curtains, portières or draperies being readily swung aside so as to admit more light, permit of easy access being had to window sashes or a door, provide a clear passageway, and prevent the curtains, portières, draperies from being blown about or 20 soiled by dirt and dust, particularly when a window or door is open.

Another object of my invention is to furnish a window frame with a novel support 25 for the confronting free ends of pivoted curtain rods, thus preventing the rods from sagging or bending due to the weight of curtains, portières, or draperies suspended therefrom.

30 A further object of my invention is to provide a simple, durable, inexpensive and easily adjusted and installed curtain fixture that can be readily finished to harmonize with its support and present a neat and attractive appearance in a room or other compartment.

I attain the above and other objects by a mechanical construction that will be herein-after specifically described and then claimed, 40 and reference will now be had to the drawings, wherein—

Figure 1 is a perspective view of a curtain fixture, without curtains, and with one of the pivoted rods swung to one side;

45 Fig. 2 is a plan of a curtain fixture with the pivoted rods in a closed position;

Fig. 3 is a front elevation of a curtain fixture provided with sets of curtains;

Fig. 4 is a front elevation of a portion of 50 the fixture;

Fig. 5 is a detail view of a portion of the fixture illustrating a slight modification of my invention, and

55 Fig. 6 is a cross sectional view of a curtain rod showing one way of attaching curtains to the same.

In the drawing, the reference numeral 1 denotes a portion of a window, door or alcove frame and mounted at the sides of the frame, in vertical alinement, are sets of bearings 2 each bearing consisting of a plate adapted to be attached to the frame 1 by screws or other fastening means, and a projecting apertured lug at the upper edge of the plate. 60

Pivoted in the bearings 2 are curtain rods, comprising vertically disposed shank portions 3 journaled in the bearings 2, with crank portions 4 and 5 at the ends thereof. The crank portion 4 at the lower end of the 70 curtain rod serves as a handle by which the shank portion 3 may be easily turned in the bearings 2, and the crank portion 5 is of greater length than the crank portion 4 so that when the curtain rod is in a closed position the crank portion 5 will support a lateral portion 6 of said rod away from the lintel or upper rail of the frame 1. As shown, the crank portion or handle 4 is in a vertical plane parallel with the plane of 75 the lateral portion 6, so that when it is desired to swing the lateral portion 6 to an open position, as shown in Fig. 1, a similar movement is imparted to the crank or handle 4. The long crank portion 5 of the rod 80 normally rests upon the uppermost bearing 2 and the crank portion or handle 4 is sufficiently removed from the lowermost bearing 2 to permit of the shank portion 3 of the rod being shifted vertically to facilitate 85 moving the lateral portion 6 of the rod, as will hereinafter appear.

Attached to the lintel or upper rail of the frame 1, intermediate the ends thereof, is the plate 7 of a bracket arm 8 said plate 95 being connected to the frame by screws or other fastening means. The bracket arm 8 projects outwardly from the frame and has the outer end thereof provided with a compound curved or grooved support or ledge 100 9 adapted to receive and hold the confronting ends of the lateral portions 6 of the curtain rods. When the curtain rods are swung to a closed position, the lateral ends thereof engage and ride over a cam surface 10 forming part of the support 9 and in doing so the curtain rods are slightly elevated, but eventually have the ends thereof seat in the grooved portion of the support 9. This support cooperates with the uppermost bearings 2 in firmly holding the lateral portions 6 of the curtain rods, so that one or more cur- 110

tains may be suspended from each rod. For instance, in Figs. 3 and 6 of the drawings, there are shown curtains 11 having cases 12 to receive the lateral portions 6 of the curtain rods, and these curtains may be in the form of marginal decorations at the sides and top of the window frame, while additional curtains, portières or draperies 13 may be suitably attached, for instance by stitches 10 or pins, to the cases 12, whereby the fixture will have a highly decorative effect. To prevent the curtains of each rod from becoming accidentally displaced when the rods are swung to an open position, the ends of the 15 lateral portions 6 are provided with spaced openings or apertures 14 for cotter pins 15 or similar retaining members, and these cotter pins are set in sufficiently from the ends of the lateral rod portions 6 so as not 20 to interfere with the ends of the rods riding on to and seating in the support 9.

For fear that a gust of wind may accidentally open the curtains, I may provide the upper ends of the shank portions 3 of the 25 rods, below the uppermost bearings 2, with coiled compression springs 16 engaging the uppermost bearings 2 and cross heads 17 carried by the shank portions 3. The expansive force of these small springs will 30 hold the shank portion 5 seated upon the uppermost bearings 2 with the ends of the lateral portion 6 seated in the support 9. To open the curtain rods it will then be necessary to slightly elevate the same where-

by the confronting ends of the rods may 35 freely ride out of engagement with the central support 9.

It is thought that the operation and utility of the curtain rods will be apparent without further description, and while in the drawings there are illustrated the preferred embodiments of my invention, it is to be understood that the structural elements are susceptible to such variations and modifications as fall within the scope of the appended 45 claim.

What I claim is:—

A curtain fixture comprising vertically alining bearings adapted for attachment to the sides of a frame, a support adapted for attachment to the top of the frame, one piece curtain rods having shank portions journaled in said bearings and cranks at the ends of the shank portions of said rods with lateral curtain supporting portions carried 55 by some of said cranks and adapted to engage said support, pins in the lateral curtain supporting portions of said rods adapted for retaining curtains in engagement therewith, and springs on the shank portions of said 60 rods holding the curtain supporting portions thereof normally seated on said support.

In testimony whereof I affix my signature in the presence of two witnesses.

ADDIE DEMING.
